DECORATIVE SILL AND RAIL COMBINATION
FOR AUTOMOBILE WINDOWS

Robert G. T. Reilly, Tustin, Calif., assignor to Autogear
of California, Orange, Calif.

Filed June 15, 1970, Ser. No. 23,478

Term of patent 14 years

Int. Cl. D12—16

U.S. Cl. D14—6

FIG. 1 is a perspective view showing the upper and outer portions of the decorative sill and rail combination for automobile windows;

FIG. 2 is a bottom plan view thereof;

FIG. 3 is a side elevation thereof, showing the inner side;

FIG. 4 is an end elevation thereof, as viewed from the left in FIG. 3;

FIGS. 5 and 6 are, respectively, enlarged transverse sectional views taken on lines 5—5 and 6—6 of FIG. 3; and

FIG. 7 is a side elevation, showing the outer side.

I claim:

The ornamental design for a decorative sill and rail combination for automobile windows, substantially as shown and described.
